Primary Examiner — Marianne Pandozzi*Assistant Examiner* — Jae Liang(74) *Attorney, Agent, or Firm* — Weide & Miller, Ltd.(57) **CLAIM**

The ornamental design for a cup with ring, as shown and described.

DESCRIPTION

FIG. 1 is a perspective view of a cup with ring showing my new design;

FIG. 2 is front view thereof;

FIG. 3 is side view thereof;

FIG. 4 is a rear view thereof;

FIG. 5 is a top view thereof; and,

FIG. 6 is a bottom view thereof.

The broken lines in the drawing depict portions of the cup with ring that form no part of the claimed design.
